UNITED STATES PATENT OFFICE.

CECIL E. BRIGHAM AND CHARLES R. ROWE, OF EAST ORANGE, NEW JERSEY, AS-
SIGNORS TO BRANDES LABORATORIES, INC. OF NEWARK, NEW JERSEY, A COR-
PORATION OF NEW JERSEY.

CIRCUITS FOR ELECTROMAGNETIC SOUND REPRODUCERS.

Application filed November 16, 1925. Serial No. 69,386.

To all whom it may concern:

Be it known that we, CECIL E. BRIGHAM and CHARLES R. ROWE, citizens of the United States, residing at East Orange, in the county of Essex and State of New Jersey, have invented certain new and useful Improvements in Circuits for Electromagnetic Sound Reproducers, of which the following is a specification.

10 Our invention relates broadly to electromagnetic sound reproducers and more particularly to a construction of electromagnetic sound reproducer for the efficient reproduction of music and voice frequencies.

15 One of the objects of our invention is to provide a plurality of magnetic circuits for a loud speaker or electromagnetic sound reproducer used in radio reception, each of which may be efficiently responsive to a particular range of frequencies so that the integral effect of all of the circuits is the efficient reproduction of sound at good tone qualities.

20 Another object of our invention is to provide a loud speaker having a plurality of branch circuits therein each efficiently responsive to a particular range of frequencies for the efficient reproduction of signaling energy of widely varying frequencies and the stressing of all of the notes of differing tone quality to bring out the various inflections of the sound.

25 Still another object of our invention is to provide a plurality of circuits in an electromagnetic sound reproducer which may be selected for connection in the output circuit of an electron tube amplification system in order to change the impedances of the reproducer to match the impedance of tubes of different characteristics.

30 Our invention will be more clearly understood from the following specification by reference to the accompanying drawings, wherein:

35 Figure 1 is a cross-sectional view taken through an electromagnetic sound reproducer embodying the principles of our invention; Fig. 2 illustrates one arrangement of branch circuits which we may employ in a loud speaker; Fig. 3 illustrates a modified arrangement of branch circuits which comprise the electromagnetic system of the loud speaker; Fig. 4 shows another circuit arrangement for the circuits of a loud speaker

whereby the high and low notes are efficiently reproduced; Fig. 5 illustrates a construction of switching arrangement for controlling the circuits within the loud speaker; and Figs. 6 and 7 show different arrangements of the loud speaker windings which may be secured by manipulation of the switching arrangement of Fig. 5.

40 Our invention contemplates the connection of a plurality of branch circuits in the output of an electron tube audio frequency amplifying system which comprise the electromagnetic windings which actuate the diaphragm of the sound reproducer. We have discovered that sound of widely varying frequency may be efficiently reproduced by providing two independent circuits in the electromagnetic sound reproducer, one of which comprises a low frequency unit and the other of which forms a high frequency unit. The low frequency unit is arranged to have a high inductance, while the high frequency unit has a low inductance. The high frequency unit may be tuned by means of a condenser interposed in series with the high frequency unit. By the arrangement of the multiple circuits in the electromagnetic sound reproducer a faithful reproduction of all of the varying tone frequencies may be secured.

45 Referring to the drawing in more detail, we have shown in Fig. 1 an electromagnetic sound reproducer embodying the improvements of our invention. Reference character 1 designates a casing having a downwardly depending annular ring portion 2 therein forming a mounting for a sound reproducing diaphragm 8 in the upper portion of the reproducer. An acoustic horn is suitably supported in a ferrule member 3 screw threaded at 4 into the sound reproducer casing. The interior of the sound reproducer casing 1 is screw threaded at 5 enabling an annular ring member 6 to be adjusted therein for supporting the diaphragm 8 on an upwardly extending annular rim 7 carried thereon. The electromagnetic driving mechanism is carried by a rotatable plate member 9 screw threaded into the lower portion of the casing 1 and rotatable therein under control of a lever 10. A pair of angle pieces 11 comprising the poles of the electromagnetic sound reproducer are carried by the rotatable plate member 9 by means of terminal

members 12 and 14. A suitable permanent magnetic system 15 is provided for cooperation with the pole pieces 11. The pole pieces 11 are extended vertically to a greater extent than has heretofore been normal in electromagnetic sound reproducers and adjacent the top of the pole pieces 11 we provide bobbins 16 and 17 which are wound in such manner as to provide a circuit resonant to the high notes with a condenser 20 in circuit therewith. Below the bobbins comprising the high frequency unit of the receiver we provide magnet bobbins 18 and 19 which comprise the low frequency unit. The wiring arrangement of the sets of units in the output circuit of an electron tube is more clearly illustrated in Fig. 2 where the units are connected in the plate circuit of an electron tube 21 and utilized to impress the magnetic effect thereof upon the diaphragm 8. In Fig. 3, we have shown the several sets of windings designed for the high and low frequency notes parallel connected in the output circuit of electron tube 21 without the inclusion of a condenser in series with the high frequency winding.

In Fig. 4 we have shown the sets of windings connected in series, with the condenser 20 in series with the bobbins 16-17 forming the high frequency unit. In Fig. 5 we have shown diagrammatically an electromagnetic sound reproducer wherein the pole pieces 11 are wound separately with bobbins 22 and 23 with the terminals thereof brought out to sets of contacts 27 and 28 which may be controlled by spring strip members 25 and 26 under the action of the push-pull switch 24 to connect the windings 22 and 23 as represented in Fig. 6, or in parallel as represented in Fig. 7 for changing the impedance of the electromagnetic sound reproducer to match the impedance of electron tubes of different characteristics. We may also provide a switching means for the arrangement of windings and associated condenser in the assembly illustrated in Fig. 1.

It will be understood that by the arrangement of high and low frequency units, the entire range of audio frequency notes may be reproduced with maximum efficiency for obtaining perfection in the reproduction of varying frequencies.

While we have described our invention in certain particular embodiments, we desire that it be understood that modifications may be made and that we intend no limitations upon the invention other than those imposed by the scope of the appended claims.

What we claim and desire to secure by Letters' Patent of the United States is as follows:

1. In an electromagnetic sound reproducer, the combination of an electromagnetic driver, a diaphragm actuated by said driver, a plurality of windings carried by said

electromagnetic driver, each of said windings being efficiently responsive to a particular range of audio frequency notes, said windings being positioned adjacent each other on said electromagnetic driver for combining their effects for operation of said diaphragm over the entire audible range of voice frequencies.

2. In an electromagnetic sound reproducer, the combination with a casing, of an electromagnetic driver positioned therein, a diaphragm carried within said casing and arranged to be actuated by said electromagnetic driver, said electromagnetic driver including a plurality of independent windings, each of said windings being efficiently responsive to a selected range of audio frequency notes, whereby said electromagnetic driver operates said diaphragm over the combined range of said audio frequency notes.

3. An electromagnetic sound reproducer comprising in combination, a casing, an electromagnetic driver positioned within said casing, a diaphragm carried within said casing for actuation by said electromagnetic driver, said electromagnetic driver including a pair of pole pieces, each of said pole pieces having a plurality of windings thereon, said windings being connected in separate circuit and responsive to different ranges of audio frequency notes, whereby said electromagnetic sound reproducer is efficiently responsive over the entire audible range of frequencies.

4. An electromagnetic sound reproducer comprising in combination a casing, an electromagnetic driver carried within said casing, a diaphragm positioned in said casing and actuated by said electromagnetic driver, said electromagnetic driver including a pair of extended pole pieces, a plurality of windings carried by said pole pieces, said windings being separately responsive to particular bands of frequencies for operating said electromagnetic driver efficiently over the entire range of audible frequencies.

5. An electromagnetic sound reproducer comprising in combination a casing, an electromagnetic driver carried within said casing, a diaphragm positioned in said casing and actuated by said electromagnetic driver, said electromagnetic driver including a pair of extended pole pieces, a plurality of windings carried by said pole pieces, said windings each having values of inductance proportioned to each other in such manner that a plurality of said windings are efficiently responsive to one band of audio frequencies, while others of said windings are efficiently responsive to another band of audible frequencies for the efficient reproduction of sound over the entire audible range.

6. An electromagnetic sound reproducer comprising in combination a casing, an elec-

tromagnetic driver carried within said casing, a diaphragm positioned in said casing and actuated by said electromagnetic driver, said electromagnetic driver including a pair of extended pole pieces, a plurality of windings carried by said pole pieces, a condenser arranged within said casing and having a value related to the inductance of one pair of said windings for the efficient 10 reproduction of the higher audible notes and another pair of said windings having an inductance value proportioned for the efficient reproduction of the lower band of audible notes, whereby all of said windings 15 operate to efficiently reproduce sound over the entire range of audible frequencies.

7. An electromagnetic sound reproducer comprising in combination a casing, an electromagnetic driver carried within said casing, a diaphragm positioned in said casing and actuated by said electromagnetic driver, said electromagnetic driver including a pair of extended pole pieces, a plurality of pairs of windings carried by said pole 25 pieces, one pair of said windings having a value of inductance so proportioned that the higher audio frequency notes may be reproduced thereby and another pair of said windings having an inductance of such 30 value that the lower audio frequency notes may be efficiently reproduced thereby, with the windings having characteristics for the efficient reproduction of the higher audio frequency notes positioned adjacent the upper 35 extremities of said pole pieces, while the windings proportioned for the efficient reproduction of the lower audio frequency notes are positioned adjacent the lower portions of said pole pieces in such manner that 40 the conjoint action of said windings serves to actuate said diaphragm over the entire range of audible frequencies.

8. An electromagnetic sound reproducer comprising in combination a casing, an electromagnetic driver positioned within said casing, a sound reproducing diaphragm car-

ried within said casing and actuated by said electromagnetic driver, a pair of pole pieces for said electromagnetic driver, independent sets of windings positioned on 50 said pole pieces, one set of said windings having a low inductance value, while the other set of said windings has a high inductance value, with a condenser positioned in series with said first mentioned set of 55 windings and having a value such that a high reactance is offered for the range of frequencies for which the other set of windings responds and a relatively low reactance for higher audio frequencies, whereby said 60 diaphragm may be efficiently operated over the entire audible range of notes.

9. An electromagnetic sound reproducer comprising in combination a casing, an electromagnetic driver positioned within said 65 casing, a sound reproducing diaphragm carried within said casing and actuated by said electromagnetic driver, a pair of pole pieces for said electromagnetic driver, independent sets of windings positioned on 70 said pole pieces, one set of said windings having a low inductance value, while the other set of said windings has a high inductance value, with a condenser positioned in series with said first mentioned 75 set of windings and having a value such that a high reactance is offered for the range of frequencies for which the other set of windings responds and a relatively low reactance for higher audio frequencies, said first mentioned set of windings being positioned on the upper extremities of said pole pieces adjacent said diaphragm, while the other set of said windings is positioned adjacent the lower portion of said pole pieces, whereby said diaphragm may be efficiently operated over the entire audible range of notes.

In testimony whereof we affix our signatures.

CECIL E. BRIGHAM.
CHARLES R. ROWE.
